CLAIM

The ornamental design for a rack for dishwasher, as shown and described.

DESCRIPTION

FIG. 1 is a front perspective view of the rack for dishwasher showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a partial enlarged view of the area '9' as identified in FIG. 6;

FIG. 10 is a front perspective view of the rack for dishwasher showing the tines folded;

FIG. 11 is a front view of FIG. 10;

FIG. 12 is a back view of FIG. 10;

FIG. 13 is a left side view of FIG. 10;

FIG. 14 is a right side view of FIG. 10;

FIG. 15 is a top plan view of FIG. 10;

FIG. 16 is a bottom plan view of FIG. 10;

FIG. 17 is a partial enlarged view of the area '17' as identified in FIG. 10; and,

FIG. 18 is a partial enlarged view of the area '18' as identified in FIG. 15.

The broken lines depict portions of the rack for dishwasher that form no part of the claimed design. The dash-dot broken lines are to show enlargement and form no part of the claimed design.
